UNITED STATES PATENT OFFICE.

ANDREW W. STEIGER, OF HARTFORD, CONNECTICUT, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,299,052.

Specification of Letters Patent. Patented Apr. 1, 1919.

Application filed March 30, 1918. Serial No. 87,672.

To all whom it may concern:

Be it known that I, ANDREW W. STEIGER, a citizen of the United States, residing in Hartford, in the county of Hartford and State of Connecticut, have invented certain new and useful Improvements in Combined Type-Writing and Computing Machines, of which the following is a specification.

This invention relates to combined type-writing and computing machines, and more particularly to means whereby the pointing off or spacing between figures, as between dollars and cents, and between hundreds and thousands, etc., may be done automatically in the regular course of writing numbers, and is herein disclosed in the nature of an improvement on the application of Frederick A. Hart, No. 79,969, filed February 23, 1916, (now Patent No. 1,282,823, dated October 29, 1918).

In the application above referred to, the mechanism includes an escapement wheel with which co-operates a fixed dog and a loose dog, both supported by a dog rocker, the latter controlled by character keys to effect letter-feed movements of the typewriter carriage. Said application also includes mechanism for effecting a double-space movement of the carriage at a point where it is desired to have a space between figures, by automatically shifting a stop member, which controls the throw of the loose dog, by means of a bail provided with tappets, the tappets being engaged by a projection on a tabulator stop during the travel of the typewriter carriage.

An object of the present invention is to provide means whereby, when the computing machine is disconnected, the space skipping mechanism is also rendered inoperative. As herein disclosed, this result may be accomplished by swinging the tappeted bail to a position where it will not be engaged by the tabulator stop, by means of a disconnect or non-add key.

The present invention as herein shown is applied to a combined typewriting and computing machine of the type shown in the patent to Hanson, No. 816,319, dated March 27, 1906, and in the patent to Frederick A. Hart, No. 1,188,933, dated June 27, 1916.

Other features and advantages will hereinafter appear.

In the accompanying drawings,

Figure 1 is a transverse vertical section of the machine, some of the parts being broken away, others being omitted.

Fig. 2 is a detail front elevation of the upper portion of the tabulator plunger bracket, showing part of the means supported thereby for causing the typewriter carriage to skip a space at predetermined positions during the travel thereof.

Fig. 3 is a skeleton perspective view illustrating my invention, and showing the connection between the non-add key and a pivoted frame which supports the tappeted bail.

Fig. 4 is a fragmentary front elevation of the typewriter escapement which shows the parts set so as to allow the typewriter carriage to be moved single letter-space distances.

Fig. 5 is a similar view with the escapement dogs rocked rearwardly.

Fig. 6 is a view similar to Fig. 5, except that the stop member is shifted to effect a double-space movement of the typewriter carriage.

Fig. 7 is a developed diagrammatic view showing enough of the machine to show the application of my invention in a simple manner.

The typewriting machine, except some of the escapement devices which will hereinafter be clearly described, is of the usual Underwood construction, in which numeral keys 11 and alphabet keys 12 when depressed, move key levers 13 and 14 respectively, and rock bell cranks 15 to swing type bars 16 upwardly and rearwardly about a fulcrum rod 17, causing types 18 and 19 to print against a cylindrical platen 20 rotatably mounted on the typewriter carriage 21.

The typewriter carriage is under constant tension of the spring drum 22 connected to the typewriter carriage by a strap 23. A rack 24 pivotally mounted on the typewriter carriage at 25, engages with the pinion 26 to rotate an escapement wheel 27 provided with teeth 28. The pinion 26 is connected to the escapement wheel by the usual one-way driving pawls 29. This escapement wheel co-

operates with a loose dog 30 and a fixed dog 31 mounted on the dog rocker 32 which is pivotally supported by an escapement bracket 33.

5 The typewriter escapement, except the double-space feature herein described, is in many respects like that described in the patent to Rice *et al.*, No. 769,804, dated September 13, 1904, and is operated in the following manner.

10 Each type bar 16 is provided with a heel 35 which, while the type bar is swinging to printing position, moves a universal bar 36 rearwardly against the tension of a spring 37 (Fig. 3) and rocks the dog carrier against the tension of a spring 38 (Fig. 4). The spring 38 serves the double function of swinging the loose dog about its pivot 39 when the upper part of the dog carrier is 15 moved rearwardly, and returning the dog carrier to normal position. During the operation of the type bars 16, the dog rocker 32 is caused to vibrate transversely of the escapement wheel 27, thus bringing the teeth 28 of the escapement wheel into co-operation alternatively with the loose and fixed dogs.

15 When the dog rocker or carrier is moved rearwardly, the loose dog 30 is disengaged from a tooth 28 of the escapement wheel after the fixed dog 31 has moved into a position to engage said tooth and hold the escapement wheel. The loose dog 30, when thus disengaged, is permitted under the influence of the spring 38, to move to a position where it is arrested by a stop 40 (Fig. 5), and when the dog rocker is brought back to normal position, the loose dog will be brought into the path of the next succeeding tooth 28 20 of the escapement wheel 27, and the fixed dog will be withdrawn from the path of the teeth. The wheel being now free, is rotated, causing said succeeding tooth 28 to swing the loose dog about its pivot 39 back to normal position (Fig. 3) against a stop 41 on the dog carrier 32, thereby arresting the carriage after a letter-space movement thereof.

25 The tabulator, except some of the stops on the stop bar, is of the regular Underwood construction, in which a depression of one of the denominational tabulator keys 45 swings a lever 46 about a fulcrum 47, to move the upper end of a plunger 48 into the path of a column stop 49 supported on a stop bar 50 carried by the typewriter carriage. The plunger 48 during such movement releases the typewriter carriage by engaging with a pivoted universal bar 51, causing a downward movement of the link 52 30 which swings the lever 53 about its pivot 54, and raises the rack 24 out of engagement with the pinion 26, thus setting the carriage free from the escapement devices, and permitting it to be moved by the spring drum 22. The carriage will run until a col-

umn stop 49 strikes the projected plunger 48, thereby arresting the carriage at the column position determined by said stop 49, and at the denominational position in the column corresponding to the actuated key 45. In 70 the present case I have shown eight plungers, each one being provided with a key 45 and a lever 46.

75 The computing mechanism comprises the usual denomination-selecting tappet 59 which, during part of the travel of the typewriter carriage rides upon a cam roller 60, located under a set of jacks 61 to rock them one at a time, and move corresponding thrust rods 62 downwardly. Each of the 80 rods 62 swings a lever 63 about a fulcrum 64, said levers each causing one of the linkages 65 to raise one of the computing bars 66 so that the pins 67 thereon are brought into co-operative relation with the linkages 85 68. If a numeral key 11 is now depressed, a stem 69 on the key lever 13 rocks a shaft 70 to move its corresponding linkage 68 and set a pin 67 on the computing bar 66. Thus the lower end of the pin 67 will be in a position, 90 when the computing bar 66 is lowered, to be engaged by a horizontal bar 71 which forms part of a general operator adapted to be operated by a handle 72.

95 When the handle 72 is operated, the computation is completed on the computing wheels 73, substantially in the manner described in said Hanson Patent 816,819.

To disconnect or, in other words, to make the computing mechanism inoperative when writing numbers in the computing zone, the cam roller 60 is moved rearwardly where it will not engage with the tappet 59 during the travel of the typewriter carriage. This is accomplished by actuating a non-add key 100 105 80 which moves a thrust rod 81 to rock a lever 82 about its pivot 83. A roller 84 on the lever 82 engages with an arm 85 to rotate a rock shaft 86, thus moving a frame 87, 110 to carry the cam roller 60 out of the path of the tappet 59, against the tension of the usual spring 87, which normally holds the tappet effective at this zone.

115 To lock the computing mechanism in the disconnect position, there is provided a pin 88 projecting laterally from the thrust rod 81 into a slot 89 formed in the casing 90. By bringing the pin 88 to the depression 91 of the slot 89, the thrust rod may drop its pin 120 therein and thus be prevented from returning to normal position.

125 Double-space movements of the typewriter carriage at predetermined positions during its travel are effected in the following manner.

The stop 40 which normally controls the swinging escapement dog 30 as hereinbefore described, is carried on a shiftable stop member or lever 95 pivoted on a stud 96 secured to the escapement bracket 33, the le- 130

ver being held in position lengthwise of the stud by nuts 97 and 98 (Fig. 3). A second stop 99 on said lever 95 is so positioned that when the lever is rocked from the Fig. 5 position to the position indicated in Fig. 6, the stop 99 is brought into the path of the dog 30. It should be understood that in the Fig. 5 position the swinging dog 30 is arrested by a pin 100 coming in contact with the stop 40, and in the Fig. 6 position the loose dog is arrested by the round portion 101 engaging with the stop 99. If the dog rocker 32 is now rocked to disengage the fixed dog 31 from the escapement wheel, the latter is permitted a double-space movement as one tooth 55 has been skipped by the pivoted or loose dog 30.

The shiftable stop member 95 is connected through an arm 103 thereon and a link 110 to a bail 107, said bail and stop member being held in normal position by a spring 102, which causes the arm 103 to bear against the escapement bracket 33. The stop member 95 is rocked to its double space feeding position, (Fig. 6) against the tension of the said spring 102, in the following manner.

Those of the tabulator stops 49 which are used to stop the carriage at computing zones in which it is desirable to skip the punctuation spaces, are provided with extensions 105 which during the travel of the carriage engage with tappets 106 on the bail 107, which is pivoted to a bail-carrying frame 108 by pivot screws 109. The forward portion of the bail is depressed whenever the extension 105 engages with one of the tappets 106, which causes the stop member 95, connected to said bail by means of the link 110, to be shifted to the Fig. 6 position, where the stop 40 has been taken out of, and the stop 99 brought into, coöperative relation with the loose dog 30.

To explain more clearly the double space movements of the typewriter carriage, let it be assumed that the carriage has reached the ten thousand dollars position in an adding zone. In this position the extension 105 of the tabulator stop 40 will be to the right and adjacent to the middle tappet 106. If we now print in this position, the escapement mechanism will operate as usual to permit the carriage to advance a single letter space distance on the return stroke of the type-bar. This movement of the carriage, however, will cause the tabulator stop to swing the bail 107 and through the link 110, shift the stop 99 to the Fig. 6 position, so that on the next depression of the numeral key (the carriage now being in the thousands position) the loose dog 30 is drawn by its spring 38 to the position shown in Fig. 6, where the dog 30 is arrested by the stop 99. When the dog rocker returns to normal position at the rise of the numeral key, the loose dog is to the left of the adjacent tooth 28

and so engages with the next tooth beyond that, permitting a double space movement of the escapement wheel before the dog 30 is brought to rest against the stop 41, with the result that the carriage is fed two letter spaces. Automatic double spacing is in like manner effected at the decimal point position and at any other desired points in the computing zone by correspondingly located tappets 106.

To make the double space mechanism ineffective, which is desirable when the computing machine is set to non-add or disconnect, I have found it advantageous to pivot the bail-carrying frame 108 on the tabulator plunger bracket 111, by means of screws 112, so that the upper end of the frame 108 can be moved forwardly to bring the tappets 106 on the bail 107 to the dotted line position A shown in Fig. 1, where the tappets 106 are out of the path of the projection 105 of the tabulator stop 40. The tappets 106 are moved to the dotted line position, above referred to, by pushing the non-add key 80, causing a pin 115 projecting laterally from the thrust rod 81 to rock a bail 116 by means of an arm 117, which is pivoted to the bail at 118 and held against a pin 119 projecting from the bail, by means of a spring 120. When the bail 116 is rocked, it causes a downward pull on the link 121 connected to an arm 122 extending forwardly and laterally from the bail-carrying frame 108.

It should be understood that the stop member 95 is left undisturbed while the tappets are being shifted to the A position, above referred to, the link 110 swinging about its point of connection to the stop member 103.

Furthermore the tappets 106 can be locked in their inoperative position, when the computing mechanism is locked in its disconnect position as hereinbefore described, by bringing the pin 88 on the thrust rod 81 to the cut-out portion 91 of the slot 89.

The arm 117 is pivoted to the bail 116 and held against the pin 119 by means of the spring 120, thus providing a yielding connection between the thrust rod 81 and the bail 116 to permit a movement of the thrust rod 81 after the bail 116 has come to its final position.

It is also to be understood that the bail 116 is pivotally mounted on the rod 123 and is held in place thereon against lateral displacement by collars 124 which are secured to the rod 123.

The bail-carrying frame 108, as heretofore mentioned, is pivotally mounted on the tabulator plunger bracket 111 by screws 112. These screws are fixed to said bracket by means of nuts 125 and 126 which are threaded on the screws 112 and allow an adjustment of the frame 108 and thus an adjustment of the tappets 106, so that the latter co-

operate with the tabulator stop at the proper time during the travel of the typewriter carriage. It will be seen that the screws 112 have reduced portions 127 which bear in 5 holes 128 in the plunger bracket 111.

Variations may be resorted to within the scope of the invention, and portions of the improvements may be used without others.

Having thus described my invention, I 10 claim:

1. In a combined typewriting and computing machine, the combination of a carriage, a variable feed escapement for said carriage, a tabulator stop, means controlled 15 from said tabulator stop for permitting double space letter-feed movements of the carriage at predetermined positions in its travel, computing mechanism, and means for simultaneously rendering said double-space 20 permitting mechanism and said computing mechanism inoperative.

2. In a combined typewriting and computing machine, the combination of a carriage, variable feed escapement mechanism 25 for said carriage, a tabulator stop, means controlled from said tabulator stop for effecting double space letter-feed movements of the carriage at predetermined positions in its travel, computing mechanism, a disconnect key for rendering said computing mechanism inoperative, and means for rendering said double-space escapement mechanism ineffective when said key is set to disconnect.

3. In a combined typewriting and computing machine, the combination with a paper carriage, of numeral keys, numeral types actuated thereby to print, pin bars comprising settable pins, means actuated by 40 the numeral keys for setting said pins, computing wheels, means to run up on said wheels numbers corresponding to the setting of said pins, escapement mechanism to control the letter-feed movements of the carriage to select the pin bars, means to automatically effect a double-space letter-feed movement of the carriage when the latter reaches a predetermined denomination during the writing of a number, and a key for 50 simultaneously silencing the selecting of the pin bars and the double-spacing mechanism.

4. In a combined typewriting and computing machine, the combination with a carriage and propelling means therefor, of numeral keys, types operated thereby to print, computing mechanism controlled by said keys, a tappet movably mounted on the machine frame, means on the carriage to shift said tappet when the carriage reaches a predetermined denominational position in the writing of a number, means operated by said tappet to effect a double letter-space movement of the carriage, a bar, and means actuated thereby to silence the computing

mechanism and to shift said tappet to make 65 said double-spacing mechanism ineffective.

5. In a combined typewriting and computing machine, the combination with a carriage and propelling means therefor, of numeral keys, numeral types operated thereby 70 for printing numbers, computing mechanism controlled by said keys, letter-feed mechanism controlled by said keys and operable to effect letter-feed movement of the carriage at each operation of a key, means operable 75 automatically to control the letter-feed mechanism and to effect an unequal spacing between the several digits of the number being written, and means adapted to be operated to simultaneously render ineffective 80 said computing mechanism and said variable spacing mechanism.

6. The combination with a carriage and propelling means therefor, of letter feed-mechanism normally operative to effect 85 single letter-space movements of the carriage, a machine frame, a swinging frame thereon, a tappet movably mounted on the swinging frame, means on the carriage to move said tappet when the carriage reaches 90 a predetermined position, means operated by said tappet to automatically effect a double letter-space movement of the carriage, computing mechanism, a key operable to silence the computing mechanism, and means 95 actuated by said key to move said swinging frame and thereby move said tappet to ineffective position.

7. A non-computing key, a lever operated thereby, a bail connected to the lever, and 100 double-spacing means operated by the bail and controlling the letter-space mechanism for double-spacing at the decimal position in writing a number.

8. In a combined typewriting and computing machine, the combination with a traveling carriage and a letter-feeding escapement therefor, of tabulating stops settable on said carriage, counter-stops adapted to bring said carriage to rest by said settable stops, an extension on one of said settable stops adapted to cause said carriage to feed a double letter-space, a computing device, a denomination-selector for said computing device adapted to be set in alinement with said last-named 110 stop, and means to make said selector ineffective, said means adapted automatically to make said last-named stop ineffective to cause a double feeding of the carriage.

9. In a combined typewriting and computing machine, the combination with a typewriter carriage, of escapement devices adapted to feed said carriage letter-space distances, a connection adapted to cause said escapement devices to feed said carriage a 125 double letter-space at predetermined intervals, computing devices, a denomination-selector for said computing devices, means

for supporting said denomination-selector in effective position, a key for positively making said support ineffective, a bail normally effective to cause said predetermined letter-space feeding, and a yielding connection between said key and said bail adapted to yieldingly shift said bail to ineffective position.

10. In a combined typewriting and computing machine, the combination with a traveling carriage, and escapement devices normally feeding said carriage single letter-spaces, of computing mechanism, a denomination-selector for said computing mechanism carried by said carriage, a support for said selector, a key, a connection from said key to said support for positively making it ineffective, a rack bar forming part of said carriage, a bail adjacent said rack bar adapted when moved to make said escapement devices effective to feed said carriage two letter-spaces, a tappet settable on said bar to move said bail to effect such double letter-spacing, a link for swinging said bail out of the path of said tappet, and a yielding connection from said key to said link.

11. In a combined typewriting and computing machine, the combination with a traveling typewriter carriage and escapement devices therefor adapted normally to feed said carriage single letter-spaces, of a carriage-controlled means for making said escapement devices effective to feed a double letter-space, a link extending from said carriage-controlled means adapted to make it effective, a computing device, a bar adapted to make said computing device ineffective, a floating bell crank adapted to be moved by

said bar, a pivoted arm on which said floating bell crank is mounted, a pin on said pivoted arm, a spring normally drawing said bell crank against said pivot, and a link connected to be operated by said pivoted arm and adapted to control said escapement.

12. In a combined typewriting and computing machine, the combination with a traveling carriage, and an escapement mechanism therefor including a dog, of computing mechanism, a denomination-selector for the computing mechanism, means for making said selector ineffective, a device for causing the carriage to vary the effectiveness of the dog to vary the spacing of the carriage, a pivoted arm floatingly supporting said device, and a bar for operating said means and swinging said device on its arm to simultaneously make said device and said selector ineffective.

13. In a combined typewriting and computing machine, the combination with computing mechanism, of a carriage for determining computing zones wherein said computing mechanism is effective, means for propelling said carriage, double-spacing mechanism for said carriage, a member traveling with said carriage for controlling said double-spacing mechanism, means for enabling said member to control said double-spacing mechanism in a computing zone, and means for preventing said double-spacing mechanism from being controlled by said member.

ANDREW W. STEIGER.
